OIL BURNER

Charles T. Asbury, Elkins Park, Pa.

Application January 21, 1939, Serial No. 252,202

6 Claims. (Cl. 158—77)

This invention relates to new and useful improvements in oil burners and more particularly to oil burners of the rotary head wall-flame type.

As is well known, fuel oils for domestic oil burner firing are numerically graded in relation to their volatility, viscosity, flash-point, etc. according to standards determined by the National Bureau of Standards, and current standards for such oils are set forth in a pamphlet entitled "Commercial Standard CS12-38." These fuel oils, beginning with No. 1, which is a relatively volatile high grade oil, are of decreasingly lower grade to No. 6 which is of relatively high viscosity.

It is well known in both the fuel oil and oil burner industries that domestic oil burners of the rotary head wall-flame type as now constructed, for the most part, require the use of a moderately volatile fuel oil such as No. 2 to the exclusion of the use of lower grade low viscosity fuel oils such as No. 3 which, in addition to having a higher B. t. u. rating, usually is less expensive than No. 2 oil.

After many months' work on the problem, I have found that this condition apparently results from the fact that in the rotary head type oil burners now on the market the fuel oil is discharged from the distributor or head in the form of more or less compact jets or streams, while air for mixture with the fuel to insure combustion thereof is discharged by the head from below the point of discharge of the oil.

With the foregoing observations in mind, the present invention consists essentially in the discovery that by causing the relatively compact streams of fuel oil to be distributed over a relatively large area in the form of a thin film prior to being discharged radially from the head, and at the same time causing the air for combustion to be discharged from above the point of discharge of the fuel oil, so that it contacts and mixes with the oil in a region radially remote from the head, I am able to burn lower grade fuel oils of higher B. t. u. rating than has heretofore been possible in burners of the type mentioned.

These results apparently are due to two factors. In the first place, since the oil is spread out over a relatively large area prior to discharge, in contrast to the relatively dense compact streams heretofore used, instantaneous ignition of lower grade more viscous fuels may be effected and, secondly, by discharging the air from the head above the point of discharge of the fuel, the air tends to mix with the fuel at a distance relatively remote from the head, rather than substantially at the point of discharge of the fuel as occurs when the air is discharged at or below the level of fuel discharge, and any ten-

dency for the lower grade fuels to burn back to the periphery of the head is eliminated.

The principal object of the invention therefore is to provide a rotary head wall-flame type of oil burner wherein the fuel oil is discharged radially from the head in the form of a relatively thin film or sheet and the air for combustion thereof is discharged by said head from above the point of discharge of the fuel so as to mix with the latter in a region relatively remote from the head.

The invention also consists in certain novel features and details of construction and arrangement hereinafter fully set forth and shown 15 in the accompanying drawings, in which:

Figure 1 is a fragmentary view in section vertically through a rotary head type oil burner embodying the present invention.

Figure 2 is a detached view in perspective partly in section of the head portion of the burner illustrating certain details of the construction thereof.

Figure 3 is a view similar to Figure 1 illustrating a modified form of the invention;

Figure 4 is a top plan view of the modification shown in Figure 3; and

Figure 5 is a fragmentary view in section showing a modified arrangement of heat shield for the fan and baffle construction shown in

30 Figure 1.

Referring now more particular to Figures 1 and 2 of the drawings, reference numeral 1 designates the main supporting frame of the burner which comprises an annular wall member 2 provided with lugs 2a for the reception of threaded leg members 3 which extend into supporting cylinders 4 provided with suitable base members 5. Mounted on each threaded member 3 is a lock nut 6 that rests on top of the cylinders 4 so that the frame 1 can be leveled, raised and lowered to a desired position and locked in place. The annular wall member 2 is further provided with an annular lip 7 to receive the edges of the plates 8 which support the refractory hearth tile or brick 9.

A motor 10 is suitably secured centrally with respect to the frame 1 and arranged with its shaft 11 extending axially upward through the annular wall member 2 thereof, the lower end of the shaft 11 of the motor 10 being journaled and supported in a ball race or bearing 12.

An oil distributor head designated generally as 13 having relatively large air openings 13a is mounted upon the upper end of the motor 10 shaft 11 by means of a central boss 14, and an oil supply pipe 15 provided with an outwardly re-bent tip 16 is supported from and extends upwardly adjacent the motor 10 so that said tip 16 overhangs a channel member 17. The channel member 17 is provided with an upward-

ly and outwardly sloping outer wall 18 and this terminates in a horizontal flange 19 whose outer edge portion 20 is re-bent around a flange 21 at the periphery of the distributor head 13. Extending diagonally upward and outward from the distributor head 13 are one or more radial oil distributor passages 22 and the inner ends of these communicate with the underside of said head 13 at the upper inner edge surface of the channel outer wall 18.

A feature of the invention resides in the novel construction and arrangement of a combination fan and baffle member designated generally by reference numeral 23 and mounted upon the motor shaft 11, above the head, for rotation therewith. The said fan and baffle member 23 are suitably spaced above the distributor head 13 by means of a sleeve 24 and said fan and baffle member and the distributor head 13 are secured tightly upon the shaft 11 for rotation therewith by means of a nut or the like 25. As shown in Figures 1 and 2 of the drawings the fan and baffle member 23 is of generally inverted dish shape having an imperforate top or cover section 26 and depending peripheral wall portion 27 provided with a series of openings 28 and blades 29 constituting a fan or blower. Adjacent the lower end of said peripheral portion 27 the said wall extends downwardly at an obtuse angle with respect to said portion 27 as indicated at 31 to form a lower imperforate baffle or ring portion spaced outwardly adjacent the outlet ends of the oil distributor passages 22. It is also contemplated to provide the member 23 with a heat shield 32 arranged outwardly adjacent the baffle 31 for the purpose of maintaining the latter relatively cool and thereby minimizing the formation of carbon on said baffle.

Thus the fan which provides air for combustion of the oil fuel is disposed above the points of oil discharge and in operation of the device, as the head 13 and channel member 17 rotate together with the fan and baffle member 23, the oil, fed to said channel member 17 by the pipe 15, works its way upwardly along the wall 18 thereof and into the passages 22 through and by means of which said oil is flung radially against the inner surface of said baffle portion 31 of the member 23. As the oil impinges against the baffle 31 the obstruction afforded by the latter causes said oil to spread or thin out over a relatively large area in the form of a film which flows downwardly along the inner wall of said baffle 31 to the lower edge thereof from which it is flung radially outward to a point adjacent the wall of the furnace.

As the oil fuel is thus thinned out and discharged from the lower end of the baffle, the blades 29 in the upper portion 27 of the member 23 function as a fan or blower to draw air upwardly through the opening in the hearth provided by the annular frame 2 and thence upwardly between the channel 17 and shaft 11 and openings 13a in the head 13 as well as upwardly through the space between said head 13 and baffle 31 after which it is discharged outwardly through the openings 28 and radially from the member 23 for mixture with the underfed fuel at a point radially remote from the burner structure.

The various details of construction of the fan and baffle member just described may of course be varied so long as the previously mentioned essential features are retained, and a modified form thereof which gives satisfactory results is

shown in Figures 3 and 4 of the drawings. In this form the fan and baffle member is designated 33 and generally speaking is of annular or ring form having an inner wall portion 34 providing a baffle spaced outwardly adjacent the oil discharge passages 22 and an outer wall portion 35 providing a heat shield intermediate the baffle 34 and which functions in a manner similar to the shield 32 to maintain said baffle 34 substantially cool thus minimizing carbon forming on the baffle.

The baffle ring is mounted upon the motor shaft 11 by means of a spider structure 36 located within the annular baffle and provided with a central boss 37 for reception of said shaft, a nut 38 being employed to secure the said fan and baffle member 33 on the shaft 11 for rotation therewith. A unique feature of this particular form of the device is the fact that the spokes or elements of the baffle supporting spider structure 36 are of radially increasing width and provided with a definite curvature declining in the direction of their leading edge to constitute fan blades. The blades thus provided by the spokes of the spider 36 function, after the manner of the blades 29 previously described, to draw air upwardly through the hearth opening and thence upwardly between the channel 17 and shaft 11 and openings 13a in the head 13 as well as upwardly through the space between the latter and the baffle 34 after which it discharges and mushrooms outwardly and downwardly for mixture with the underfed fuel at a point radially remote from the burner structure, the oil being discharged from the lower edge of said baffle 34 in the form of a thin film after discharge from the passages 22 against the inner surface of the baffle in the manner previously described.

A modified form of heat shield for the fan and baffle member 23 shown in Figures 1 and 2 is shown in Figure 5 of the drawings. In this arrangement the heat shield 32a forms an integral part of the member 23 and is formed by upwardly turning the lower edge of the portion 31 constituting the baffle. This particular arrangement of the heat shield provides an upwardly opening channel 39 which, during rotation of the burner head, catches a portion of the air discharged by the blades 29 of the fan which aids in maintaining the baffle portion 31 relatively cool.

In the two forms of rotary head burners illustrated and described herein it will be observed that substantially all of the air drawn through the hearth opening defined by the annular wall member 2 is caused to be discharged from a point above that of the fuel discharge, thus preventing mixture of the air and fuel at a point adjacent the periphery of the head as is the case when the air is discharged at or below the level or point of fuel discharge, and insuring such fuel and air mixture taking place in a region radially remote from said head. This arrangement together with that of impinging the streams of oil against a baffle to disperse them over a large area in the form of a film prior to discharge for combustion enables the efficient burning of lower grade fuel oils of higher B. t. u. rating than heretofore possible thus affording a greater heat output per unit quantity of fuel at generally decreased cost.

While certain particular embodiments of the invention have been illustrated and described herein, it is not intended that the invention be precisely limited thereto but that changes and modifications may be incorporated and embodied therein within the scope of the annexed claims.

In this connection, it is pointed out that successful operation of the device is not confined to baffle structures which rotate with the fuel distributor head but that equally successful results are obtained with the use of a stationary baffle and the limitation of the disclosure herein to devices embodying rotating baffles is solely because such arrangements are deemed the more practical from the standpoint of simplicity and cost of manufacture.

I claim:

1. In a burner structure of the type described, the combination with a head rotatable about a vertical axis and having means for laterally discharging streams of liquid fuel, of a structure mounted above said head and rotatable therewith comprising a depending baffle disposed in the path of said streams of liquid fuel and against which said streams impinge and disperse in the form of a thin film prior to discharge radially outward therefrom, means disposed at a level above said rotatable fuel stream discharging head for entraining air and discharging the same from above the fuel discharge for admixture with said fuel in a region radially remote from the rotatable head to form a combustible mixture, and means disposed outwardly adjacent said baffle constituting a shield for the baffle against the heat of combustion of said mixture.

2. In a burner structure of the type described, a head rotatable about a vertical axis constructed and arranged for laterally discharging streams of liquid fuel comprising an annular fuel receiving channel member and a head element superimposed thereon provided with at least one laterally directed fuel discharge passage and an upwardly directed air opening, and a structure mounted above said head and rotatable therewith comprising a depending baffle disposed laterally adjacent the outlet end of said fuel discharge passage and against which fuel discharged from said passage impinges and is dispersed in the form of a thin film prior to discharge radially therefrom, and means disposed at a level above said baffle and fuel discharge head for entraining air upwardly through the discharge head and its air opening and between said fuel discharge head and the baffle and discharging the same from above the fuel discharge region for admixture with said fuel in a region radially remote from the head to form a combustible mixture.

3. In a burner structure of the type described, a head rotatable about a vertical axis constructed and arranged for laterally discharging streams of liquid fuel comprising an annular fuel receiving channel member and a head element superimposed thereon provided with laterally directed fuel discharge passages and upwardly directed air openings, and a structure mounted above said head and rotatable therewith comprising a depending baffle disposed laterally adjacent the outlet ends of said fuel discharge passages and against which the streams of fuel discharged from said passages impinge and disperse in the form of a thin film prior to discharge radially therefrom, means disposed at a level above said baffle and fuel discharge head for entraining air upwardly through the discharge head and its air openings and between said fuel discharge head and the baffle and discharging the same from above the fuel discharge region for admixture with said fuel in a region radially remote from

the head to form a combustible mixture, and means disposed outwardly adjacent said baffle constituting a shield for the baffle against the heat of combustion of said mixture.

5. In a burner structure of the type described, a head rotatable about a vertical axis constructed and arranged for laterally discharging streams of liquid fuel comprising an annular fuel receiving channel member and a head element superimposed thereon provided with laterally directed fuel discharge passages and a plurality of upwardly directed air openings; a baffle disposed laterally adjacent the outlet ends of said fuel discharge passages and against which the streams of fuel discharged from said passages impinge and disperse in the form of a thin film prior to discharge radially therefrom, and draft inducing means disposed at a level above said fuel discharge head and rotatable therewith for entraining air upwardly through the discharge head and its air openings and between said fuel discharge head and the baffle and discharging the same from above the fuel discharge region for admixture with said fuel in a region radially remote from the head to form a combustible mixture.

10. In a burner structure of the type described, a head rotatable about a vertical axis constructed and arranged for laterally discharging streams of liquid fuel comprising an annular fuel receiving channel member and a head element superimposed thereon provided with laterally directed fuel discharge passages and a plurality of upwardly directed air openings, a baffle disposed laterally adjacent the outlet ends of said fuel discharge passages and against which the streams of fuel discharged from said passages impinge and disperse in the form of a thin film prior to discharge radially therefrom, means disposed at a level above said fuel discharge head and rotatable therewith for entraining air upwardly through the discharge head and its air openings and between said fuel discharge head and the baffle and discharging the same from above the fuel discharge region for admixture with said fuel in a region radially remote from the head to form a combustible mixture.

15. In a burner structure of the type described, a head rotatable about a vertical axis constructed and arranged for laterally discharging streams of liquid fuel comprising an annular fuel receiving channel member and a head element superimposed thereon provided with laterally directed fuel discharge passages and a plurality of upwardly directed air openings, a baffle disposed laterally adjacent the outlet ends of said fuel discharge passages and against which the streams of fuel discharged from said passages impinge and disperse in the form of a thin film prior to discharge radially therefrom, means disposed at a level above said fuel discharge head and rotatable therewith for entraining air upwardly through the discharge head and its air openings and between said fuel discharge head and the baffle and discharging the same from above the fuel discharge region for admixture with said fuel in a region radially remote from the head to form a combustible mixture, and means disposed outwardly adjacent said baffle constituting a shield for the baffle against the heat of combustion of said mixture.

20. In a liquid fuel burner structure of the type described, a head rotatable about a vertical axis and having at least one opening therein for laterally discharging a stream of liquid fuel, depending baffle means rotatable with said head and disposed in the path of discharge of the fuel stream for engagement by said stream and operable to disperse the same into a relatively thin film and then discharge the same radially outward from the lower edge of said baffle means, and means also rotatable with said head for discharging air laterally outward from the burner structure for admixture with said discharged fuel, the point of air discharge from the burner structure being at a level above the point of fuel discharge from the baffle and the spacing of said level of air discharge above said point of fuel discharge being such that mixture and combustion of said discharged air and fuel takes place only in a region radially remote from the point of fuel discharge from said baffle means.

CHARLES T. ASBURY.
